DESIGN FOR A CARBURETOR

Richard E. Schmidt, Philadelphia, Pa., assignor
of forty per cent to Harry W. Cullen, Catons-
ville, Md., and thirty per cent to Walter E.
Smith, Westchester, N. Y.

Application May 1, 1939, Serial No. 84,703

Term of patent 7 years

To all whom it may concern:

Be it known that I, Richard E. Schmidt, a citizen of the United States, residing at Philadelphia, in the county of Philadelphia and State of Pennsylvania, have invented a new, original, and ornamental Design for a Carburetor, of which the following is a specification, reference being had to the accompanying drawing, forming part thereof.

Figure 1 is a side elevational view of a carburetor showing my new design.

Figure 2 is a side elevational view showing the opposite side of Figure 1.

Figure 3 is an edge elevational view taken from the left of Figure 1.

Figure 4 is a top plan view.

I claim:

The ornamental design for a carburetor, as shown,

RICHARD E. SCHMIDT.
